UNITED STATES PATENT OFFICE.

CARL ADOLPH HAUSSER, OF PHILADELPHIA, PENNSYLVANIA, ASSIGNOR TO C. A. HAUSSER & SON, OF PHILADELPHIA, PENNSYLVANIA, A FIRM CONSISTING OF CARL ADOLPH HAUSSER AND ANTHONY ADOLPH HAUSSER.

HÆMACYTOMETER.

Application filed April 11, 1921. Serial No. 460,564.

To all whom it may concern:

Be it known that I, CARL ADOLPH HAUSSER, a citizen of the United States, residing in Philadelphia, Pennsylvania, have invented certain Improvements in Hæmacytometers, of which the following is a specification.

My invention relates to improvements in hæmacytometers, one object of the invention being to provide a supporting and protective frame or casing, said frame preferably being such that the structure, usually of glass, which constitutes the counting chamber, is easily removable therefrom and reinsertable therein, this construction having further in view the provision in connection with said frames of sets of counting chamber structures, including all forms suited to the various uses of the device, all of the structures of the set being adapted to the said frame and interchangeable therein.

Another object of the invention is to provide novel and improved means for supporting the cover plate above the counting chamber, insuring an accurate disposition of the said cover plate relative to the counting chamber.

A still further object is to provide means for clamping the cover plate in position over the counting chamber, said clamping means being such as to insure the retention of the cover plate in place with no distortion of the cover plate.

The manner in which these and other objects appearing hereinafter are attained is illustrated in the attached drawings, in which:

Figure 1, is a view in perspective of an assembled hæmacytometer made in accordance with my invention;

Fig. 2, is a view in perspective of a "single" counting chamber structure detached from the frame;

Fig. 3, is a side elevation of my improved hæmacytometer;

Fig. 4, is a sectional elevation taken on the line 4—4, Fig. 3;

Fig. 5, is an inverted perspective of the frame, and

Fig. 6 is a view in perspective of a "double" counting chamber structure.

With reference to the drawings, Fig. 1 illustrates a preferred form of my protective frame, said frame in the present in-

stance consisting of a body portion 1 having in the face thereof and extending from one end to a point short of the other end, a longitudinal recess 2, the opposite longitudinal sides 3, 3, of which are beveled, and which thereby is adapted to receive a counting chamber structure 4 of the type shown in Fig. 2, whose side edges 5, 5, are beveled to correspond with the beveled edges of the said recess, said structure 4 being adapted to be slid into the recess from the end of the frame. Also adapted to occupy the said recess is a follower 6 having its edges beveled in the manner of those of the counting chamber structure and being adapted also to be slid into place in the outer end of the said recess after insertion of the counting chamber structure, thereby to retain the said structure firmly in the inner end of the recess. A suitable retaining device is provided for locking the said follower 6 in place in the recess and to prevent outward movement thereof, said retaining element in the present instance consisting of a latch member 7 pivoted at one end to one side of the end surface of said frame and having a hook 8 at the outer or free end which is adapted to engage a suitable projection or pin 10 at the opposite side of the said end surface. The retaining element may be made of spring metal having a natural outward tendency so that when the end is once hooked over the projection 10, it will be retained thereon by frictional engagement.

I have in the present instance provided the bottom of the said frame with legs or pedestals 11 which are trued up in such fashion that when the frame rests on a plane surface the face of the counting chamber is disposed parallel with the said supporting surface.

It will be clear that with a device of this nature not only is superior protection afforded to the comparatively fragile counting chamber structure, but the assembled device may be handled with great ease. I have found that bakelite is an excellent material of which to form the protecting frame of the hæmacytometer, although any material suitable for the purpose may be employed.

It will be noted that the counting chamber structures are of the same general form

as those shown and described in the patent to Max Levy, No. 1,214,331, dated January 30, 1917, with the exception that the body of the structure is reduced to the minimum dimensions required by the counting chamber, this reduction in size, of course, being made possible by the use of the protective frame previously described.

As clearly illustrated, the counting chamber structure consists of a body portion 12 having at a side thereof spaced parallel channels 13, 13, extending completely across the body, that portion 14 of the body lying between the said channels having its surface 15 slightly lower than the top surfaces of the two side portions 15, 15, which bound the outer sides of the said channels. The two side portions 15 are comparatively narrow, and as shown in Fig. 6, I may, where a double counting chamber is desired, provide a cross channel 16 substantially the depth of the said channels 13 and extending through the side portions 15 and intermediate portion 14 and being preferably centrally disposed and at right angles to the said channels 13. This cross channel 16 I make of generous width, and so am able to prevent the passage of a liquid from one side of the counting chamber to the other side, as often happens in the double counting chambers of the usual form due to capillary attraction, since any excess blood or fluid entering the said channels 13 and 16 may pass off from the counting chamber through the side portions 15 by reason of the said channel 16 which, as previously described, extends therethrough. This has been found a decided advantage.

I also provide means for insuring the accurate support of the cover plate 20 above the counting chamber, this means consisting of a plurality of elevated supports or pedestals 21 on the side portions 15, upon which pedestals or supports the said cover plate is adapted to rest. Thus, for example, in the double counting chamber illustrated in Fig. 6, I provide four pedestals, two on each of the side portions and disposed directly opposite the rulings 22 on the central part of the chamber which define the area in which the counting is to be done. In the case of the single chamber shown in Fig. 2, I prefer to employ a three-point support, one of the supporting pedestals 21 being established on one of the side portions 15 directly in line with the ruling 22 on the central portion of the chamber, and the other two pedestals being evenly spaced apart upon the opposite side portion of the counting chamber.

Means is also provided for clamping the cover plate in position above the counting chamber, said means being in the form of resilient clips 25 of generally U-shape formation which are adapted to be slipped over

the edge of the casing and to bear with one of its arms upon the top of the cover plate, said clips being two in number and being adapted to be placed on opposite sides of the frame, preferably at the points of the pedestals 21, as most clearly shown in Fig. 1. This form of clamp in no way interferes with the manipulation of the haemacytometer, and while clamping the cover plate firmly in position, cannot distort the cover plate in any manner, particularly when properly applied so as to overlie the said supporting pedestals.

I claim:

1. In a haemacytometer, a slide comprising a frame of relatively non-breakable material, and a counting chamber structure detachably secured in said frame.

2. In a haemacytometer, a slide comprising a frame of non-fragile material, a counting chamber structure mounted in the frame, and positive locking means on the frame insuring retention of the counting chamber.

3. A haemacytometer consisting of a slide including a counting chamber, that portion of the slide constituting the counting chamber being detachable; substantially as described.

4. In a haemacytometer, a slide comprising a detachable counting chamber and a main body portion of non-fragile material to which the counting chamber is detachably secured.

5. In a haemacytometer, the combination with a frame having an aperture therein, of a translucent structure constituting a counting chamber adapted to be detachably retained in the frame over said aperture, and positive locking means on the frame insuring retention of the counting chamber.

6. In a haemacytometer, the combination with a structure constituting a counting chamber, of a frame having a central aperture therein, and a recess in one side extending inwardly from an edge of the frame, the said counting chamber structure and recess having interengaging side edges adapted to retain the said structure in the recess after insertion, a follower insertable in said recess for retaining the said structure in position overlying said aperture, and means for retaining the said follower in the recess.

7. In a haemacytometer, the combination with a structure constituting a counting chamber, of a frame adapted to receive and detachably retain said structure, and having at the bottom thereof a plurality of spaced projections adapted to elevate the body of the frame above a supporting surface.

8. A haemacytometer comprising a body having in the face thereof two spaced parallel channels bounding an area constitut-

ing the counting chamber or chambers, and a channel intersecting said parallel channels and dividing the said chamber area and extending from one edge of the body to the other.

9. A hæmacytometer comprising a counting chamber structure having three substantially parallel portions separated by a pair of spaced channels, and elevations upon the outer of said parallel portions constituting a support for a cover plate over the counting chamber.

10. A hæmacytometer comprising a counting chamber structure having three substan-

tially parallel portions separated by a pair 15 of spaced channels, a plurality of elevations upon the outer of said parallel portions, a cover plate resting upon said elevations, and independent means acting at the points of said elevations for clamping the 20 cover plate to the chamber.

11. In a hæmacytometer, a slide comprising a counting chamber, that portion of the slide constituting the counting chamber being translucent, and the remainder of the 25 slide being opaque.

CARL ADOLPH HAUSSER.
